V. ROSS

TRIMMING DEVICE

Filed June 9, 1924

FIG. II

FIG. III

FIG. IV

INVENTOR

V. ROSS

BY *Wright & Chen*
ATTYS

UNITED STATES PATENT OFFICE.

VICTOR ROSS, OF BOTHELL, WASHINGTON.

TRIMMING DEVICE.

Application filed June 9, 1924. Serial No. 718,701.

To all whom it may concern:

Be it known that I, VICTOR ROSS, a citizen of the United States, residing at Bothell, in the county of King and State of Washington, have invented new and useful Improvements in Trimming Devices, of which the following is a specification.

This invention relates to a novel and useful device for trimming bushes, grape vines, trees, shrubbery, etc., and resides in the provision of a simply constructed one man machine which may be conveniently attached to and supported by the user or operator and manipulated with little or no effort to effectively trim or cut tree, shrubbery, etc. the machine being especially useful to gardeners and farmers.

An object of the invention is to provide an extensible frame for supporting a revolving cutter and cutter operating mechanism, said frame being of a length and so constructed that when attached to the operator, may be swung or moved into position to permit of use of the cutter without requiring that the operator stoop and otherwise assume uncomfortable or tiring positions.

A further object is to provide a device of the character described which is comparatively inexpensive, reliable in operation and so constructed and arranged as to permit of a more rapid, effective, comfortable, easier and thorough trimming or pruning operation at a greater saving in time and labor than is possible under the ordinary pruning or trimming operations.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a side elevation of the device of my invention shown as when in use.

Fig. 2 represents a top plan view of the device.

Figure 3 is a longitudinal vertical section of the cutting mechanism and the adjacent portion of the support therefor.

The embodiment of my invention shown

in the accompanying drawing comprises an extensible support designated by the numeral 1, supporting at one end a rotary cutting mechanism 2, and at its other end operating mechanism 3, and attaching means 4.

The support comprises a main bar or elongated frame 5 having a longitudinal slot 6 opening at the outer end of the frame in which slot an extensible bar 7 is slidably mounted, there being registering holes in the bars 8 and 9 for reception of pins 10, to permit of holding the extensible bar in adjusted position. The support preferably has a length of about 3 feet, and can be extended from $1\frac{1}{2}$ feet to 3 feet, these dimensions being subject to change as desired.

The cutter mechanism comprises a four bladed cutter 11 turning on a hub portion 12 fixedly mounted at the outer end of the bar 7. A guard member 13 is fastened to the bar 7 in any suitable manner and supports a bearing 14 for the hub of the cutter. This guard has three radially projecting loops 15 through which the cutter blades rotate and certain edges of the loops are serrated or notched as at 16 so as to grip and hold the leaves, twigs, branches, etc., in position to be cut by the blades.

A beveled gear 17 is attached to the center of the cutter and meshes with a similar gear 18 on an extensible shaft 19. The shaft is journaled at one end in the hub 14 and at a point between its ends in a handle 20 which is carried by the main frame or bar 5. The other end of the shaft carries a beveled gear 22. This gear engages a bearing 23 on the main frame and thus holds one part of the extensible shaft against longitudinal movement. The shaft is made of telescopic splined sections as shown, and when the support is extended or adjusted, the shaft is adjusted longitudinally accordingly. A bevel gear 24 meshes with the gear 22 and is carried on a shaft 25 journaled in the bracket 21. This shaft has a wheel 26 fixed thereto and the wheel is provided with a handle 27 to provide for turning it and operating the mechanism so as to rotate the cutter.

The attaching means comprises an arcuate plate 28 having a central ball and socket joint 29 with the inner end of the support. This plate is adapted to fit the curve of the body of the operator at the waist line and is provided with loops or eyes 30 through which the belt 31 of the operator is inserted

to hold the plate and device in place. As a further means for attaching and supporting the device a shoulder strap 32 is employed, said strap being inserted through an opening 33 in the handle 20 and adjusted to support the device in the desired position. This relieves the strain on the arms of the operator and provides for a comfortable and effective operation of the device.

10 When the device is fixed to the operation as shown in Fig. 1, the support with the cutter thereon may be moved to various positions with the left hand while turning the operating mechanism with the right hand, whereby the cutter may be brought to the desired point or elevation for cutting or trimming shrubs or other growths, depending on the use of the device. The special manner of supporting the device provides for an easy and comfortable operation thereof and permits of an effective cutting or trimming action.

15

20

I claim:

1. A trimming device comprising a support, an elongated extensible support, a

30 cutter mounted on the extensible portion of the support, means operable from the other end of the support for operating the cutting mechanism, means for attaching the support to the body of the operator, an arcuate plate adapted to fit the body at the waist line and having eyes through which the belt of the operator may be passed and a universal joint connection between the plate and said support.

35 2. A trimming device comprising a support, an elongated extensible support, a cutter mounted on the extensible portion of the support, means operable from the other end of the support for operating the cutting mechanism, means for attaching the support to the body of the operator, an arcuate plate adapted to fit the body at the waist line and having eyes through which the belt of the operator may be passed, a universal joint connection between the plate and said support and a shoulder strap adapted to engage the support intermediate of its ends and to extend over the shoulder of the operator.

40 45 VICTOR ROSS.
